UNITED STATES PATENT OFFICE.

WILLIAM D. SKIDMORE, OF PELHAM, NEW YORK.

DUMPING-CAR.

1,154,446.

Specification of Letters Patent. Patented Sept. 21, 1915.

Original application filed April 9, 1914, Serial No. 830,744. Divided and this application filed November 3, 1914. Serial No. 870,071.

To all whom it may concern:

Be it known that I, WILLIAM D. SKIDMORE, a citizen of the United States, and a resident of Pelham, Westchester county, 5 State of New York, have invented certain new and useful Improvements in Dumping-Cars, of which the following is a specification.

The invention relates to railroad cars, 10 more particularly to that class of cars known as dumping cars, such as are used, for instance, in railroad construction, for conveying ballast, filling material, and the like to such places as the same may be needed, and 15 dumping the same upon or at the side of the right of way, and for other similar uses; and has for its object to provide such a car which shall be simple in construction and easy of operation, and which shall be provided 20 with means for tilting the same operated by compressed air or similar power, and with means for elevating the side of the car as the car is tilted, in order that the contents of the same may be allowed to escape; 25 this application being a division of my co-pending application, filed April 9, 1914, and bearing the Serial No. 830,744.

The invention consists in the novel construction, arrangement and combination of 30 various devices, elements and parts as shown in the accompanying drawings, and herein-after more particularly described.

In the said drawings, Figure 1 is a transverse sectional view of my improved dumping car, showing the same in its horizontal or carrying position; and Fig. 2 is a transverse sectional view showing the car in its tilted or dumping position, with one sidewall elevated to allow the escape of the contents, as hereinafter described.

In carrying my invention into effect I provide for the lower part of the car a running gear of the common or any suitable form of construction, comprising suitable 45 sills, and bolsters which I have numbered 12 in the drawings, which are mounted on two bogie trucks, provided with journal boxes 13 forming the bearings for the ends of the axles of the wheels 14.

50 The upper or carrying portion of the car is suitably pivotally supported over the running gear above referred to. The method of supporting shown in the accompanying drawings will be hereinafter described, but is not claimed herein, being

claimed in a co-pending application. This carrying portion comprises a floor 15, to the under side of which are secured spreader plates 16, which are trunnioned in bearing plates 17. The floor is provided with ends 60 51, and sides 47 and 48, the latter being capable of being elevated for discharging the load, as hereinafter described. The spreader plates 16 are provided with trunnions 19, bearing in openings 18 in bearing plates 17. When the car is in its normal carrying position, as shown in Fig. 1, it is held by the toggles comprising the members 37 and 39, and by the chains 60 and 61, which pass downward around the pulleys 65 62 and 63, and are suitably secured at the end of the car.

When it is desired to tilt the car for the purpose of dumping the load the chains 60 and 61 are suitably released, and the toggle formed by the members 37 and 39 is broken, on the side toward which it is desired to dump the contents of the car, by pulling the lever 46, which operates the links 44^a and 46^a. The mechanism by which 70 the car is tilted, and which forms one of the essential features of this application, will now be described. Suitably secured to the running gear is a cylinder 56, provided with suitable ports, (not shown) and with pipes 75 leading from the brake air-supply reservoir or pipes, or some other suitable source of power, and these pipes are of course supplied with the necessary valves and with means for operating the same. This cylinder is provided with a piston 55 of the usual construction, the rod 23 of which is prolonged and provided with a rack 53. This rack gears with a pinion 52 secured to a shaft 50 to which is secured a pinion or gear 90 21 which engages with a geared rack 20 secured to the tilting body of the car. The pinion 52 may, of course, if desired gear directly with the rack 20. When air is admitted into the cylinder 56 on one side or the other of the piston 55 as the case may be, it is evident that the said piston and the rod 23 will be moved and the car body tilted. When the car body is tilted, it is of course necessary, in order to discharge 95 the load, that the side wall of the lower half of the car shall be opened to permit the escape of its contents. This is effected automatically by the following described mechanism: The sides 47 and 48 are provided at 100

105 110

each end with extensions 90, which are located outside of the ends 86 of the car body and are provided with studs 89 which when the sides are lowered or closed rest in 5 notches 80 in the end frames 91 of the car and in the ends 86 of the body. Secured to the ends 51 of the body are rollers 85. The upper and inner edges of the side extensions 90 are curved, as shown in the drawings, 10 and such curved edges bear against the roller 85. When the car body is tilted into the position shown in Fig. 2, the rollers 85, moving with car body, depress the inner ends of the extensions 90, and as the middles of such extensions are supported by the pivots or studs 89 resting in the end frames 91, the outer ends, bearing the sides 47 are elevated, as shown in said figure. When the side wall is entirely raised the inner end of 20 the extension 90 on that side of the car bears against a block 86. If the body be only partially tilted, of course only a partial elevation of the side occurs, but still enough to permit of the discharge of the contents 25 of the car.

The operation and advantages of my invention will be obvious from what has been above said.

Having thus described my invention, what 30 I claim as new and desire to secure by Letters Patent is as follows:

1. In a dumping car, the combination with running gear, end frames, means adapted to pivotally support said body upon said running gear, and means adapted when in one position to maintain said body horizontal and when in another position to allow said body to tilt; of means adapted to tilt the said body, and means adapted to elevate 35 a side wall of the said body as the same is tilted, said means comprising an extension on said side wall fulcrumed in one of said end frames, and means adapted to depress the inner end of said extension, the point 40 of engagement between the said depressing means and the said extension moving along said extension as the body is tilted.

2. In a dumping car, the combination with running gear, end frames, a car body pivotally supported upon said running gear and between said end frames, and sides for said car body provided with extensions pivotally mounted in said end frames, of means adapted to tilt said body from its horizontal 45 position and means adapted to elevate one of said sides as the car body tilts, comprising a roller upon the end of the car body adapted to bear upon the inner ends of the said extensions of said sides and to depress said inner ends and thereby elevate the outer ends bearing the sides.

3. In a dumping car, the combination with running gear, end frames, one of said end frames being provided with notches, a car 65 body pivotally supported upon said running

gear and between the said end frames, and sides for said car body, said sides being provided with extensions having studs adapted to pivotally engage with the said notches in said end frame; of means adapted to tilt said body from its horizontal position and means adapted to elevate one of said sides as the car body tilts, comprising a device upon the end of the car body adapted to bear upon the inner ends of the said 75 extensions and to depress said inner ends and thereby elevate the outer ends bearing the sides.

4. In a dumping car, the combination with running gear, end frames, each of said end frames being provided with a notch, a car body pivotally supported upon said running gear and between the said end frames, and sides for said car body, said sides being provided with studs adapted to pivotally 80 engage with the notches in said end frames; of means adapted to tilt said body from its horizontal position and means adapted to elevate one of said sides as the car body tilts, comprising a device upon the end of the car body adapted to bear upon the inner ends of the said 85 extensions and to depress said inner ends and thereby elevate the outer ends bearing the sides.

5. In a dumping car, the combination with running gear, end frames, one of said end frames being provided with notches, a car body pivotally supported upon said running gear and between the said end frames, and sides for said car body, said sides being 95 provided with extensions having studs adapted to pivotally engage with the said notches in said end frame; of means adapted to tilt said body from its horizontal position, means adapted to elevate one of said 100 sides as the car body tilts, comprising a device upon the end of the car body adapted to bear upon the inner ends of the said extensions and to depress said inner ends and thereby elevate the outer ends bearing the sides.

6. In a dumping car, the combination with a body, running gear, and means adapted to pivotally support said body upon said running gear, of means adapted when in one position to maintain said body horizontal and when in another position to allow said body to tilt, and means adapted to tilt the said body, said means comprising a piston operated by compressed air or the like, a piston rod connected therewith, a rack on said piston rod and means whereby said rack is operatively connected with said car body.

7. In a dumping car, the combination with a body, running gear, and means adapted to pivotally support said body upon said running gear; of means adapted when in one 130

- position to maintain said body horizontal, and when in another position to allow said body to tilt, and means adapted to tilt the said body, said means comprising a piston 5 operated by compressed air or the like, a rod connected with said piston, said rod being provided with a rack, a gear wheel engaging with said rack, a rack on said car body, and means whereby the motion of 10 said gear wheel is communicated to said second named rack.
8. In a dumping car, the combination with a car body, running gear, and means adapted to pivotally support said car body upon 15 said running gear, of means adapted when in one position to maintain said body horizontal and when in another position to allow said body to tilt, and means adapted to tilt the said body, said means comprising a piston 20 ton operated by compressed air or the like, a rod connected with said piston, said rod being provided with a rack, a pinion engaging with said rack, a gear wheel rigidly attached to said pinion, and a rack secured to 25 the under side of said car body, said second named rack being adapted to engage with said gear wheel.
9. In a dumping car, the combination with a car body, running gear, and means adapted 30 to pivotally support said car body upon said running gear, of means adapted when in one position to maintain said car body horizontal and when in another position to allow said car body to tilt, means adapted 35 to elevate one side of said body as the same is tilted, whereby the contents of said body is allowed to escape, and means adapted to tilt the said body, said means comprising a piston operated by compressed air or the 40 like, a piston rod connected therewith, a rack on said piston rod and means whereby said rack is operatively connected with said car body.
10. In a dumping car, the combination with a car body, running gear, and means adapted 45 to pivotally support said body upon said running gear; of means adapted when in one position to maintain said body horizontal and when in another position to allow said body to tilt, means adapted to elevate 50 the side of the said body as the same is tilted, whereby the contents of said body is allowed to escape, and means adapted to tilt the said body, said means comprising a piston operated by compressed air or the 55 like, a rod connected with said piston, said rod being provided with a rack, a gear wheel engaging with said rack, a rack on said car body, and means whereby the motion of said gear wheel is communicated to 60 said second named rack.
11. In a dumping car, the combination with a car body, running gear, and means adapted to pivotally support said car body upon 65 said running gear, of means adapted when in one position to maintain said body horizontal, and when in another position to allow said body to tilt, whereby the contents of said body is allowed to escape, and means adapted to tilt the said body, said 70 means comprising a piston operated by compressed air or the like, a rod connected with said piston, said rod being provided with a rack, a pinion engaging with said rack, a gear wheel rigidly attached to said pinion, 75 and a rack secured to the under side of said car body, said second named rack being adapted to engage with said gear wheel.

In witness whereof I have hereunto signed my name this 31st day of October 1914, in 80 the presence of two subscribing witnesses.
